UNITED STATES PATENT OFFICE

117,967

DESIGN FOR A MEAT TENDERER

Quirino Beltram, Newark, N. J.

Application August 5, 1939, Serial No. 86,485

Term of patent 14 years

To all whom it may concern:

Be it known that I, Quirino Beltram, a citizen of the United States, residing at Newark, in the county of Essex and State of New Jersey, have invented a new, original, and ornamental Design for a Meat Tenderer, of which the following is a specification, reference being had to the accompanying drawing, forming a part thereof.

In the drawing—

Fig. 1 is a perspective view as seen from above of a meat tenderer embodying my new design;

Fig. 2 is a perspective view showing the meat tenderer in inverted position.

I claim:

The ornamental design for a meat tenderer, substantially as shown.

QUIRINO BELTRAM.
